(57) CLAIM

The ornamental design for a shoe sole, as shown and described.

DESCRIPTION

FIG. 1 is a bottom, front and right side perspective view of a shoe sole in accordance with the new design;

FIG. 2 is a bottom plan view thereof;

FIG. 3 is a left side elevation view thereof;

FIG. 4 is a right side elevation view thereof;

FIG. 5 is a front view elevation thereof;

FIG. 6 is a rear elevation view thereof; and,

FIG. 7 is a partial cross-sectional view along the line 7-7 of FIG. 2.

The shoe upper shown in broken lines in FIGS. 1-6 is an illustration of environmental structure only and forms no part of the claimed design.

The trademark and logo elements shown in the shoe sole in broken lines in FIGS. 1-3 and 6 are an illustration of environmental structure only and form no part of the claimed design. The portion of the shoe upper in broken lines in FIG. 7 is an illustration of environmental structure only and forms no part of the claimed design.
